(57) **CLAIM**

The ornamental design for a steel coil sidewall guard, as shown and described.

DESCRIPTION

FIG. 1 is a perspective view of the foldable steel coil sidewall guard, having its rectangular top folded at 90°, and engaging the top of a steel coil, and its perforate front positioned against the sides of the steel coil.

FIG. 2 is a top plan view of the steel coil sidewall guard, as shown in FIG. 1.

FIG. 3 is a front view of the steel coil sidewall guard of FIG. 2.

FIG. 4 is a side view of the steel coil sidewall guard of FIG. 2.

FIG. 5 is a front view of the steel coil sidewall guard corresponding to FIG. 3, with the rectangular top being shown in its open position; and,

FIG. 6 is a perspective view of the steel coil sidewall guard, having its rectangular top folded at 90°, and engaging the top of a steel coil, and its perforate front being folded inwardly and being positioned against the sides of a steel coil.
